FUSE PLUG OR THE LIKE

Application filed November 25, 1927, Serial No. 235,612. Renewed January 23, 1931.

My invention relates to a fuse plug for electric circuits which precludes the possibility of a person inserting a coin or tin foil into the socket in order to close the circuit in the event that the fuse is blown. Furthermore it is designed to prevent the use of a fuse of larger amperage than is proper to the circuit, thereby reducing the fire hazard.

Very often when a fuse blows and another one is not easily obtainable, a makeshift connection, such as tin foil or a coin, is inserted into the socket to close the circuit. Such an expedient, although serviceable for the time being, really defeats the purpose of the fuse plug where the circuit closer is of higher fusibility than the wire in the system since the wire will melt. The melting of a wire in the circuit, such as one passing in close contact to wood, would give rise to fire.

The fuse plugs now found on the market are made in several sizes, that is to say that the fusible element is varied to fuse at different amperages. The conventional fuses are about five in number and range from thirty to ten amperes. It will be seen that in the event a ten ampere fuse should be blown and a twenty-five ampere substituted therefor, that the circuit would lose its safety factor inasmuch as the substituted fuse would have a fusibility above the danger point. By the use of my proposed fuse plug, where the same is made up in forms peculiar to each amperage, it will be impossible to interchange a fuse plug of higher amperage for one of lower amperage and conversely. As will be appreciated, by making the portion of the fuse plug which remains permanently within the socket of different tapers and the recesses of the fuse carrying elements of different tapers, each taper corresponding to a certain amperage, that it will be hardly possible to substitute a fuse carrying element of one amperage for that of another.

It is an object of my invention to provide

a fuse plug which is simple in structure and reliable in operation.

Another object of my invention is to provide a fuse plug which is fool proof and precludes the possibility of forming a makeshift connection in the socket after the fuse has blown or the use of a fuse of larger amperage.

Still another object of my invention is to provide a two part fuse plug wherein one of the complementary parts remains permanently attached within the plug socket, the other or removable part containing the fuse element; the component parts being made in varying amperage sizes, each having a different taper so that the fuse carrying members cannot be interchanged.

Other objects and advantages of my invention will be apparent from the detail description which follows.

I attain these objects and advantages by means of the device illustrated in the accompanying drawings wherein:

Figure 1 is a side elevational view of my fuse plug showing the two parts associated together.

Figure 2 is a plan view of the fuse plug showing the conventional window.

Figure 3 is a cross sectional view taken through Figure 1 showing the mode of contact between the component parts.

Figure 4 is a perspective view of the male member which is permanently attached within the socket.

Figure 5 is an end view showing a conventional fuse block fixture having a socket therein for holding the fuse plugs, in one socket the entire unit being installed.

Figure 6 is a cross sectional view taken through line B—B of Figure 5 showing the male member in place.

Similar numerals refer to similar parts throughout the several views.

Referring to Figures 1 and 2 of the drawings, the fuse plug consists of the complementary members 1 and 2. The upper or female

member 1 consists of the porcelain body 3 having the recess 4 which is adapted to receive the conical portion of the male member 2. A threaded ferrule 5 is spun around the porcelain body 3 whereby the upper member may be threaded into an electric socket. The porcelain body 3 is provided with a hollow 14 at its top part for a purpose to be described hereinafter.

10 A split rivet 6 passes through the bridge portion 7 of the porcelain body 3 and a fusible element 8 is secured to the split end of the rivet and passes at an angle through a duct in the porcelain body to the shell 5 and is soldered thereto.

15 The body portion 3 is provided with a flange 9 at its outermost part and a cap 10 is secured to this flange, the cap being fixed in place by spinning its lower edges around the flange. A window of mica or other transparent material is first interposed between the cap 10 and the flange 9 before the cap 10 is secured in place. It will be seen from Figure 2 that a large portion of the fusible element 8 is clearly visible through the window 11. In accordance with the usual practice, the portion of the fusible element which is visible through said window is provided with a thinned cross-section so that a break in the 20 fuse may be detected. The head 12 of the split rivet which is on the under side of the bridge portion 7 serves as a contact point which will be mentioned in greater detail in connection with the description of the male member 2.

25 The shell 5 and the cap 10 may be made of sheet brass or any other similar material, as this does not form a part of the invention. Likewise the fusible element may be of any 30 suitable material and those now in use are equally applicable to this fuse plug.

35 The male member 2 comprises a substantially conical member having its upper portion truncated and is preferably made of porcelain or some similar non-conducting material. A rivet member 15 passes through the axis of this member, both ends of the male member 2 being countersunk as shown in the drawings to form the recesses 16 and 18. The upper 40 end or apex of the conical member is countersunk to form the recess 16. By reason of this countersunk portion it will be appreciated that the possibility of making a contact with the shell by the use of a coin or similar makeshift is practically obviated. The head of the rivet 17 which lodges in the recess 16 may be half-headed to permit only clockwise rotation. The lower recess 18 is provided with 45 the metallic cap 19 and is of sufficient area to house the center contact of the socket. The lower end of the rivet member 15 is provided with a rivet head 20 which causes the cap member to be held tightly to the unit so that 50 the entire body of the male member may turn

with the unit when the male member is being first inserted in the socket.

55 The male member is provided with a flanged base 21 having the fins or spring clips 22 projecting from the periphery thereof and so disposed that they turn with the male member in a right-hand direction during the insertion of the same into the socket, but upon reverse rotation grip the socket and prevent the withdrawal of the male member. In view of the fact that the head 17 is half-headed to allow only clockwise rotation, it cannot be used to turn the male member against the resistance of the fins 22.

60 Referring to Figures 5 and 6 the fuse plug is shown installed in the usual fuse block provided therefor, the male member 2 being shown fixed in place, the lower recess 18 enclosing the center contact 25 of the electric socket, the ferrule of the upper portion fitting within the shell 26 of the socket.

65 The manner of use of the above described fuse plug is as follows. The lower or male member is first inserted in place by forcing it into the socket giving it a turning movement by turning the screw head 17 until the bottom of the male member is flush with the bottom of the socket. The fins allow the member to turn in a right-hand direction but in the event of reverse rotation they grip 70 the sides of the shell and prevent the withdrawal of this member. The conical member remains at all times fixed within the socket and should never be removed. The upper or female member 1 containing the fusible element is the only replaceable part of the fuse plug unit and is screwed in place until it hugs the conical portion of the lower member and contact is made. In the event that the fusible element is blown the entire upper 75 part is removed and a new one substituted.

80 As previously stated the male and female members may be made up in different sizes with different tapers, each taper being peculiar to the size of the fuse. This may be 85 done by varying the depth of the male member or changing its contour, the female fuse carrying member having a recess to conform to the male member. In this way it will be impossible to take a fuse carrying element of 90 a higher amperage and insert it into a socket containing a male member which corresponds to a lower fuse amperage and the converse is equally true. It should be noted that the male member is permanently affixed 95 within the socket and being of a particular shape that only the fuse carrying member having the recess to conform thereto may be used as otherwise the electrical connection with the center contact of the socket will not 100 be made. By reason of the fact that the socket employing the proposed fuse is not suited to receive a fuse of higher amperage nor is adapted to be closed by a coin or other makeshift, the fire hazard from the fusing 105

of electrical wiring from excess current is eliminated.

All that has been said above in the description of my preferred embodiment is offered by way of illustration and not limitation. I do not wish to be limited to the exact structure of the preferred embodiment shown and described, or to any particular material used in the construction of parts, or to the design of parts, but desire protection as against any variations in structure which utilize the principle of my invention and fall within the purview of my invention and are within the spirit and scope of the following claims.

The invention having been set forth, what is claimed as new and useful is:—

1. In combination with a socket, a fuse plug comprising a female fuse carrying element, said fuse carrying element having a tapered recess therein, a contact point in said recess, said female fuse carrying element being provided with a conductive means, a fusible element joining said contact point and said conductive means, a male member having a base substantially equal in area to that of the socket and tapering upwardly and engaged with the tapering walls of said recess, said male member being adapted to fit within said recess, means on said male member to secure it against removal from said socket, and a conductor in said male member for electrically connecting the contact in said recess and the center contact of said socket.

2. In combination with a fuse plug socket, a tapered male member affixed therein, said male member having a flange portion on its base and having aligned recesses in its base and apex, a conductor passing through said male member having its extremities in said recesses, said base recess being of such size as to house the center contact of said socket, a female fuse carrying member having a tapered recess corresponding to the taper of said male member, the sloping side walls of said tapered male member and recess being in engagement, a contact point within said tapered recess adapted to engage the upper extremity of said conductor, said female fuse carrying element being provided with a conductive means, and a fusible element passing from said point to said conductive means.

3. In combination with a fuse plug socket, a fuse plug comprising in combination a tapered member, locking means on said tapered member to prevent its withdrawal from said socket, a conductor contacting the center contact of said socket and extending to the top of said tapered member, a fuse carrying member, comprising a body having a recess on one end thereof to accommodate said tapered member and having the side wall of said recess engaged with the side wall of said tapered member, a threaded ferrule there-

around for insertion into said socket, said fuse carrying member having a recess on the other end thereof, a fusible element within said last mentioned recess, means for electrically connecting said fusible element to said socket, and a transparent medium on the top of said fuse carrying element through which the fusible element is visible.

4. In combination with a cut out, a fuse plug comprising a female fuse carrying member, a male member complementary to said fuse carrying member, said male member being adapted to be inserted within said cut out and having a tapered projection that is seated on the inclined side wall of a tapered recess in said female member, and means on said male member for locking same against removal from said cut out.

5. In combination with a cut out, a fuse plug comprising a fuse carrying member, said fuse carrying member having a tapered recess therein, a base member of insulating material being provided within said cut out, said base member being complementary to said fuse carrying member, said base member having a protuberant portion tapering upwardly, said protuberant portion being adapted to fit within and to seat on the sloping wall of said recess, and a conductor in said base member for electrically connecting the fuse carrying member to the center contact of said cut out.

6. In combination with a cut out, a fuse plug comprising a fuse carrying member, said fuse carrying member having a substantially conical recess therein, a base member of insulating material being provided within said cut out, said base member being complementary to said fuse carrying member, said base member having a substantially conical portion, said conical portion being adapted to fit within and to seat on the sloping wall of said recess, and a conductor in said base member for electrically connecting the fuse carrying member to the center contact of said cut out.

7. In combination with a cut out, a fuse plug comprising a fuse carrying member, said fuse carrying member having a tapered recess therein, a base member of insulating material being provided within said cut out, said base member being complementary to said fuse carrying member, said base member having a protuberant portion tapering upwardly, said protuberant portion being adapted to fit within and to seat on the sloping wall of said recess, and a conductor in said base member for electrically connecting the fuse carrying member to the center contact of said cut out.

8. In combination with a socket having an annular contact and a center contact, an insulating member located within said annular contact and upstanding above said center contact, a fuse-carrying plug engaged directly with said annular contact above said insulating member and surrounding and laterally

engaging said insulating member, and conducting means which passes through said insulating member and engages said center contact.

5 9. The combination defined in claim 8 wherein said conducting means is carried by said insulating member and said plug has a contact that engages said conducting means.

10. The combination of a socket having an 10 annular contact, and an insulating member which is located in the bottom of the socket and upstands therein within said annular contact and has a center contact at the top, and a fuse-carrying plug surrounding and 15 laterally engaged with said insulating member having means engaging said annular contact and a contact which engages said center contact.

11. The combination of a socket having an 20 annular contact, a center contact, and a conical insulating member which is located within said annular contact over said center contact, and a fuse-carrying member engaged with said annular contact and having a recess in which said conical insulating member 25 is seated, and means connecting said fuse-carrying member with said center contact.

12. The combination with a socket having an annular contact and a center contact, of 30 a fuse plug comprising a fuse-carrying member and a separate insulating member having a circular base which is of materially lesser diameter than said annular contact and is located therein above said center contact 35 and has a conical part which upstands above said base, and said fuse-carrying member having means engaged with said annular contact and a recess in which said conical part is laterally engaged and seated, and means 40 which passes through said insulating member and engages said center contact.

13. The combination recited in claim 12 wherein means are provided for restraining said insulating member within said annular 45 contact.

14. A fuse plug having an annular contact and a center contact and comprising a female fuse-carrying member which carries the annular contact and has a conical recess 50 in an end thereof, and complementary to said female member, an insulating male member at one end of which the center contact is exposed, said male member having a projection which is located in and is laterally engaged by the wall of the recess in said female member.

15. A fuse plug as defined in claim 14 wherein said male and female members have inter-engaging conical projections and recesses.

16. A fuse plug as defined in claim 14 combined with means which restrains said male member from removal from a receptacle for said plug.

65 17. A fuse plug having an annular screw-

threaded contact and a center contact and comprising a female member having a fusible element one end of which is connected with said annular contact, and a male insulating member at least partly located in a recess of said female member and laterally engaged by the wall of said recess and having the center contact exposed at the exposed end of said male member, and conducting means connecting the center contact with the other 70 end of said fusible element.

18. In combination with a socket, a fuse plug comprising a female fuse-carrying element having a tapered recess therein, a male member adapted to fit within said socket and having an upwardly tapering portion adapted to seat on the tapered wall of said recess, and conducting means which connects with the fuse of said fuse-carrying element adapted to pass through said male member and engage with the center contact of said socket.

19. A fuse plug having an upper fuse-carrying member and a complemental lower member, the upper member having a recessed lower end, the lower member having an upper 90 projecting portion which occupies said recess and is laterally engaged by the wall of said recess, and conducting means which is adapted to be connected with the fuse of said fuse-carrying member and which passes through said lower member and its projecting portion.

20. A socket-type fuse plug comprising an upper fuse-carrying member having an outer screw-threaded shell adapted to be screwed 100 into the socket and a complemental lower member adapted to be located in the bottom of the socket, the upper member having a conical recess in its lower end and said lower member having a conical projection which 105 is seated in said recess and against the inclined wall thereof when the plug is in the socket, and conducting means which connects the fuse with the center contact of the socket and which passes through said projection and 110 recess.

21. A socket-type fuse plug comprising an upper fuse-carrying member and a complemental lower member, said upper member having an axially located and extended recess 115 in the lower end and said lower member having a complemental projection which is seated upon the inclined wall of said recess, and conducting means which passed through said recess and projection and has connection with the fuse.

22. A socket-type fuse having an upper fuse-carrying member having a conical recess in the bottom end thereof, and a lower member that is adapted to lie in the bottom 125 of the socket over the center contact and has an upstanding conical insulating projection that is located within the recess and is seated on and centered by the sloping wall of said conical recess of said member.

23. A socket-type fuse having an upper fuse-carrying member and a lower member that is adapted to lie in the bottom of the socket over the center contact and has an
6 upstanding conical insulating projection that is located within and is laterally engaged and centered by the bottom end of said upper member, and a contact at the bottom thereof that is adapted to engage the center contact
10 of the socket.

Signed at Fall River, in the county of
Bristol, State of Massachusetts, this twenty-
second day of November, 1927.

EDWARD J. BURNS.
